ELASTIC FLUID TURBINE

Stanley Smith Cook and Louis Mortimer Douglas,
Wallsend-on-Tyne, England, assignors to The
Parsons Marine Steam Turbine Company, Lim-
ited, Wallsend-on-Tyne, England

Application July 14, 1943, Serial No. 494,638
In Great Britain July 30, 1942

4 Claims. (Cl. 253—70)

This invention relates to elastic fluid turbines of the kind comprising parallel-flow co-axial alternatively oppositely rotating turbines, the flow of elastic fluid taking place axially through each turbine toward the other turbine to enter a common exhaust chamber disposed between the turbines.

The invention consists in various features of construction and combinations of parts in an elastic fluid turbine of the kind set out above and for a full understanding of the invention a detailed description of a construction embodying the same in a preferred form will now be given in connection with the accompanying drawing forming a part of this specification and the invention then specifically pointed out in the claims.

Referring to the diagrammatic drawing accompanying this specification:

Figure 1 is a longitudinal sectional view of part of a steam turbine embodying the present invention in one form, and

Figure 2 is a developed plan thereof.

In carrying the invention into effect according to one convenient form illustrated by way of example in Figures 1 and 2, we provide a row of fixed blades K attached to a turbine stator, this row being disposed adjacent to the last row of astern turbine blades C, the blades C being mounted on a rotor A carrying also a set of ahead turbine rotor blades D. The last moving row of astern blades C discharges steam towards the ahead section whilst the last moving row of ahead blades D discharges towards the astern section, both discharging into a common chamber E enclosed by the turbine casing F.

A number of deflector devices M are attached to the blades K.

The steam leaving the radially inner portion of blades D tends to follow the path G' and that leaving the outer portion to follow the path G². As these two paths converge, the steam leaving the blades D would have to compress to follow these paths, and as there is no force available to compress the steam, the path will be substantially as indicated by the dotted lines H. It will be seen that if nothing is interposed between the ahead and astern last moving rows, the portion indicated by dimension x would strike the rotor blades C and only that portion indicated by dimension y would impinge upon the stator, with the result that less than one quarter of this steam would be effective.

The direction of the steam leaving blades D in a tangential plane is indicated by line R from the root portion and T from the tip portion of the

blades and the profile of blades K is such that the steam impinges substantially normally on portions of these blades so that its velocity is extinguished and the steam does not pass through these blades into the reversely rotating blades C of the astern turbine and cause frictional loss and overheating.

High efficiency is not of primary importance in the astern turbine but it is desirable to develop as much power as possible with a relatively small turbine and it will be seen that with the interposition of blades K the whole of the steam leaving blades C impinges upon blades K and consequently has a fully reactive effect, whereas without them the path of the steam would be somewhat similar to that indicated by the dotted lines J and the reaction of that portion represented by dimension x' would be ineffective.

Furthermore, the steam leaving blades K is, in the tangential plane, turned in the direction L with a substantial component in the direction of astern rotation so that the portion represented by x² which impinges upon the ahead rotor blades D will have a turning effect and actually increase the astern power over that developed in the normal astern blades. It frequently occurs that in turbines of the type described the area through the final moving row of blades of the astern turbine is insufficient to accommodate expansion down to the pressure in the exhaust chamber, and the steam consequently leaves these blades at a higher pressure, the further expansion to the exhaust pressure taking place in the exhaust chamber itself, after leaving the blades. The blades K are so designed that the areas for steam flow through the blade passages are such that the passage of the steam through them does not cause any, or any substantial, increase in the pressure of the steam leaving blades C.

The further expansion of the steam from the pressure at which it leaves blades C to the exhaust chamber, which expansion takes place in passing through or on leaving blades K causes the steam leaving the latter to have a very high velocity and if its path L has a substantial component in the direction of astern rotation and a considerable portion of the steam impinges upon the rotor in the direction indicated, this steam will add considerably to the power developed by the astern turbine.

The provision of the deflector device M causes all the steam from the astern turbine or at least the greater quantity thereof to follow the path indicated by lines V and consequently to impinge upon the last row of rotor blades D; the deflector

devices instead of being attached to the blades may be rigidly fixed adjacent thereto.

A series of ducts P are provided in the stator which lead from the space between the last moving row C and the shield row K to the exhaust chamber E. The ducts P are preferably arranged in the transverse plane containing the leaving edges of the blades C so that the steam pumped by the latter will pass directly into them. They are also preferably disposed, in that plane, tangentially to the outer periphery of the row of blades C to conform to the path of the steam leaving these blades when rotating in the ahead direction.

The object of the ducts P is to ventilate this space between the blades C and K when running ahead, the blades C acting as a centrifugal pump to draw a cooling stream of steam over the blades, which steam can escape into the exhaust belt through the ducts P.

We claim:

1. An elastic fluid turbine of the kind comprising parallel-flow co-axial alternatively oppositely rotating turbines, the flow of elastic fluid taking place axially through each turbine towards the other turbine to enter a common exhaust chamber disposed between the turbines, said turbine having exhaust guiding blades between the common exhaust chamber and the last row of astern moving blades and including deflecting devices thereon having exhaust guiding surfaces to direct the astern exhaust steam with axial, radial and circumferential components against at least a portion of the last row of for-

ward moving blades in a direction to give an additional turning effect to the rotor in the astern direction.

2. An elastic fluid turbine as claimed in claim 1, wherein the exhaust guiding blades are disposed immediately succeeding in the direction of flow the last row of astern moving blades and said devices are fixed to and succeed the guiding blades and have guiding surfaces with axial, radial and circumferential components.

3. An elastic fluid turbine as claimed in claim 1, in which the exhaust guiding blades have passages for the exhaust steam flow occupying the greater part of the actual space occupied by the guiding blades and said passages, whereby a large and free flow of the astern exhaust through said blades is secured and loss of exhaust velocity in passing through the guiding blades reduced.

4. An elastic fluid turbine of the kind comprising parallel-flow co-axial alternately oppositely rotating turbines, the flow of elastic fluid taking place axially through each turbine towards the other turbine to enter a common exhaust chamber disposed between the turbines, having a row of fixed blades immediately succeeding in the direction of flow the last row of astern moving blades and wherein the space separating the said row of fixed blades from the last row of moving blades on the astern turbine is furnished with ducts serving to ventilate the space when the ahead turbine is in operative rotation.
